[57] CLAIM

The ornamental design for a cushioned hanger clip or similar article, as shown and described.

DESCRIPTION

FIG. 1 is a front perspective view of a cushioned hanger clip or similar article showing my new design;

FIG. 2 is a front elevational view thereof, the rear being identical;

FIG. 3 is a side elevational view thereof, both sides being identical;

FIG. 4 is a top plan view thereof;

FIG. 5 is a bottom plan view thereof.

The characteristic feature of the design resides in the contrasting appearance of the opposed engaging lips.
